UNITED STATES PATENT OFFICE

101,238

DESIGN FOR A CHEMICAL TOILET

John R. Morgan, Oak Park, Ill., assignor to Sears,
Roebuck and Co., Chicago, Ill., a corporation of
New York

Application July 8, 1936, Serial No. 63,706

Term of patent 7 years

To all whom it may concern:

Be it known that I, John R. Morgan, a citizen of the Republic of Guatemala, residing at Oak Park, in the county of Cook and State of Illinois, have invented a new, original, and ornamental Design for a Chemical Toilet, of which the following is a specification, reference being had to the accompanying drawing, forming a part thereof.

The drawing is a perspective view of a chemical toilet embodying my new design.

The side of the device opposite to that shown in the drawing is substantially similar to the side illustrated.

I claim:

The ornamental design for a chemical toilet, as shown and described.

JOHN R. MORGAN.
